CLAIM

The ornamental design for a refrigerator undershelf drawer, as shown and described.

DESCRIPTION

FIG. 1 is a perspective view of a refrigerator undershelf drawer showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

(Continued)

The broken lines in the drawings depict portions of the refrigerator undershelf drawer that form no part of the claimed design.

1 Claim, 5 Drawing Sheets
